COOLING SYSTEM

Application filed May 11, 1927. Serial No. 190,624.

This invention relates to a cooling system and more particularly to a cooling system for a centrifugal casting mold.

The rotary or centrifugal casting process is used quite extensively in the manufacture of pipe, but is not limited to pipe casting, for any annular object may be formed by this process. While I shall illustrate my invention by a pipe casting process, it is of course to be understood that its use is not confined thereto.

Heretofore, molds have been cooled either by surrounding the mold with a water jacket or sprinkling upon the exterior of the mold a cooling medium. But regardless of the method employed there have ensued certain undesirable results.

The cooling of the entire mold is commenced at the same time. But, in the case of the last-mentioned mold, the metal is poured progressively along the length of the mold, and different portions of the mold along its length receive the poured metal at different moments. Inasmuch as the temperature of a mold depends to a large extent upon the length of time it has been subjected to a cooling effect, this means that there is a variance in the temperature of the mold along its length at the time metal is poured, for certain portions, prior to receiving molten metal, have been subjected to the cooling action for longer periods than other portions. For instance, assuming that the pouring is commenced at the bell end and terminated at the spigot end, as is usually the case, that portion of the mold at the spigot end, at the moment the metal is poured there, has been exposed to a continuous cooling, uncounteracted by the heat of molten metal, for a longer period than the bell end of the mold. As the texture of a casting operation is dependent to a certain extent upon its cooling, there has resulted a variance in the texture between the two ends of the pipe.

But a more serious problem confronted when the previous systems are employed resides in a case-chilling of the cast object. This is due to the sudden cooling of the exterior of the object. In order to render a pipe which is chilled in this manner usable in

ordinary commercial operations, it is necessary to anneal the pipe after its removal from the mold. Such a step entails additional cost of manufacture and consumes considerable time.

Aside from the deleterious effects on the casting resulting from the use of the prior cooling systems, uneven stresses are set up along the length of the mold, and it has been found that after relatively short use, the mold fails at the spigot end.

To overcome these difficulties is one of the objects of this invention.

Another object is to provide a cooling system for use in a centrifugal casting apparatus.

Still another object is to provide a cooling system whereby a mold in a centrifugal casting apparatus may be gradually cooled.

A still further object is to provide a cooling system for progressively cooling a rotary mold along its longitudinal axis.

And yet another object is a cooling system whereby the cooling of the mold is effected at a predetermined relationship to the cooling of the mold.

To accomplish these and other objects, as will more fully appear hereinafter, my invention comprises a cooling member and means to so regulate said member that the cooling effect is gradual.

Reference is made to the accompanying drawings, which set forth one embodiment of a device by the use of which the advantages of my invention may be obtained. It is of course obvious that many modifications of the apparatus herein set forth may be made without exceeding the scope of the invention.

Figure 1 is a side view of a mold and cooling system partly in elevation and partly in section;

Fig. 2 is an end elevational view of the mold and cooling apparatus shown in Fig. 1;

Fig. 3 is a cross sectional view of the valve along the line 3—3 of Fig. 1, looking in the direction of the arrows;

Fig. 4 is a partial sectional view of the valve, in detail along the line 4—4 of Fig. 3, looking in the direction of the arrows.

Fig. 5 is a side view of a mold, cooling system, and means for regulating the system;

Fig. 6 is a cross sectional view along the line 3—3 of Fig. 1, looking in the direction of the arrows, of a modified form of valve.

Fig. 7 is a cross sectional view of another modified form of valve.

Referring more particularly to Fig. 1, there is shown a mold 1 with an enlargement 2 at one end for the formation of a bell of the cast pipe. The mold is rotatably mounted upon trunnions 3, which are supported by roller boxes 4 suitably affixed to a base 5. The mold is rotated by suitable driving means, not shown. The mold is also partially supported by a bearing member 6 having grooves therein, into which fits a corresponding feather 7 on the exterior of the mold. This arrangement prevents axial movement of the mold, but permits of its rotation. The bearing may be either of the split type or have a split bushing. Supported in the bearing member 6 and also by a standard 8, suitably mounted on the base, is a chamber 9 with apertures 11. Baffles 12 are spaced within the chamber 9 forming fluid tight-sections.

To each section there is connected a feed pipe 13. Each feed pipe is independent, although all are enclosed for a portion of their lengths within a casing 14. It will thus be seen that each of the sections may be individually operated. All of the feed pipes are supplied with a cooling medium through a valve 15. The valve herein shown is of the rotary multiple type, although any other suitable valve may be employed. This valve cuts into operation successive feed pipes, which in turn fill successive sections of the dispersing chamber 9 with the cooling medium. An intake pipe 16 supplies the necessary cooling medium.

The valve is operated by a shaft 17. A fluid tight gland 18 is provided on the valve where the shaft 17 enters. A roller or gear 19 is provided on the shaft, and operative means, shown in Fig. 5, rotate the shaft 17 at a desired rate.

In Fig. 2 is shown the shape of the standard 8, although it is not necessary that it be arcuate as shown in the drawings. The casing 14 extends throughout the upright portion of the supply pipes, acting both as a protective device for the pipes and aiding in their support. The dispersing member 9 is shown held by means of an eye 20 in the standard. While I have shown only one dispersing member, it is to be understood that a plurality of such members may be provided.

Referring to Figs. 3 and 4, a disk 21, forming a water-tight connection with the body of the valve 22, is provided with an arcuate aperture 23. Ports 24 located in the valve and connected to the feed pipes by screw-threading or other suitable means, terminate in the face of the body portion 22 of the valve.

Except for the aperture 23, the disk 21 prevents the entrance of a cooling medium into the ports. The arrangement of the ports 24 is partially circular and the aperture 23 is located in the disk 21 so that it describes in its rotation the arc formed by the ports. As the disk 21 is rotated, the aperture 23 passes over the ports of the pipes in succession, uncovering successive supply pipes, which in turn feed corresponding sections in the dispersing chamber 9. In order to obtain a progression of adjacent sections of the dispersing chamber 9, ports for successive sections should be adjacent one another. The disk 21 is integral with the shaft 17, and its speed therefore may be regulated (and the rate at which successive sections are brought into operation) by the rotative regulation of the shaft 17.

In Fig. 4 there is shown a chamber 25 in which the cooling medium is held prior to its entrance in the ports. The disk 21 is held in close contact with the body 22 by suitable means, shown in this figure as a helical spring 26. A collar 27 on the shaft 17 fits in a proper well 28 on a plate 29 of the valve. The plate 29 may be detached for repairing, and is held in fluid-tight contact with the body of the valve by bolts 31. By means of the spring 26, both the disk 21 is held against the body 22 and the collar 27 is maintained in a non-leaking contact in the well 28. At points of contact between the various parts, washers or packing may be employed.

In Fig. 5, I have shown diagrammatically means for synchronizing the cooling of the mold and pouring of the metal, in order to insure cooling at a definite rate with respect to the pouring of the metal.

A carriage 32, provided with wheels 33, carries a cooling trough 34. A ladle 35 is also mounted upon the carriage 32. The carriage runs on a track 36.

There is an arm 37 on the carriage 32, which supports a sleeve 38. This sleeve takes in a worm shaft 39. Rotation of the shaft, therefore, causes the carriage 32 to be moved along the track 36.

A motor 41 is provided to drive the worm shaft 39. One end of the worm shaft terminates in a gear reducing apparatus 42, which also houses and joins the gear 19 with the worm shaft 39. The proper gearing in this rotating apparatus must be determined for each machine depending upon the rate of cooling desired. Rotation of the worm shaft therefore not only causes movement of the carriage 32, but operates the rotary valve 15 which governs the cooling.

The arrangement of this apparatus is susceptible of many modifications. It may be desirable to have a cooling of any portion of the mold coincident with the deposition of molten metal within that portion. Again it may be desirable to cool the portions prior

or subsequent to the deposition of metal within them.

These changes may be effected by adjustments of the arm 37 on the shaft 39. To secure such adjustments, the sleeve 38 may be of the split type to permit movement of the carriage 32 along the track 36 independent of the worm shaft.

While I have shown and described a casting apparatus in which the mold remains stationary and the trough moves longitudinally with respect thereto, it is to be understood that the cooling system may be adapted to a casting apparatus wherein the mold moves while the trough remains stationary, or in which both the trough and mold move.

It is sometimes desirable to vary the cooling effect in the sections during the time they are in operation. For instance, it may be desirable to cool the mold at a greater rate at the moment metal is being poured in a section and then to have the cooling decrease. Or again, it may be desirable to gradually increase the cooling of a section of the mold. Such variations may be accomplished by changing the shape of the slot 23 in the disk 21.

In Fig. 6 I have shown a slot 43 in the disk 21 whereby the amount of cooling medium entering the ports 24 decreases as the disk rotates. There is shown a port 24' fully opened, but it will be observed that as the disk 21 rotates in the direction of the arrow, the slot 43 diminishes in size and consequently 35 closes progressively the port 24'. As above stated, many variations may be desired in the cooling of a section of the mold, and such modified forms of cooling may be effected by altering the shape of the slot. For instance, 40 if the left side of the slot is smaller than the right end there would be an increase in the amount of cooling medium admitted to the ports 24 as the disk is rotated.

Where I have referred to a cooling medium, 45 any cooling fluid, either liquid or gas, is meant.

It will be noted that each section of the dispersing pipe 9 is connected with an individual feed pipe which is joined to ports 24 50 in the valve 15. The baffles 12 prevent any leakage of a cooling medium from one section to another, and the introduction of a cooling medium into one of the supply pipes means that only that section will be dispersing the medium.

The apertures 23 or 43 on the disk 21 in rotating over the ports of the supply pipes open progressively additional pipes, and in so doing permit the entry of the cooling medium into the pipes. Thus chamber 25 is kept filled by a cooling fluid entering the chamber through the feed pipe 16.

In operation, the trough shown in Fig. 5, 55 extending within the mold 1, commences the pouring operation, usually at the bell end,

and, while continuing to pour metal, is gradually withdrawn toward the opposite end. The shaft 17 may be rotated at such a rate that a new section of the dispersing member 9 will be cut into operation as the metal is 70 poured within that portion of the mold cooled by the section. This rotation may be effected by independent means such as a motor, cylinder, or other timing device, synchronized with the relative movement of the trough in 75 the mold, or it may coact directly with the trough, as above described.

The cooling systems described above comprehend an incremental cooling. In these systems additional cooling segments are added to those already in operation, the addition of the segments being at a determined rate with respect to the pouring of molten metal 80 within the mold.

It may be desirable however to cool the 85 mold by a section which progresses, by steps, along the length of the mold as metal is poured within it. There is shown in Figure 7 a modified form of valve to accomplish such a cooling. The disk 21 is provided with an 90 aperture 44, which uncovers only one port 24 at a time, in contradistinction to the slot 23 or 43 which on opening a port does not close the preceding port.

The disk 21 shown in Figure 7 rotates, as 95 in the case of the other disks, but the aperture 44 uncovers only one port. As an additional port is opened the face of the disk 21 covers up the preceding port. With this arrangement the sections in the cooling member 9 are progressively brought into operation. As each compartment commences to disperse a cooling medium, the preceding section ceases to function. In this way there will be a spray of cooling medium dispersed 100 on the mold, the length of the spray being that of the sections in member 9, and the cooling progresses by steps along the length of the mold 1.

Many modifications may be made in the 110 disk 21 to give varied cooling to the mold, and I have set forth only a few such modifications in this application. It is to be understood that variations made in the shape and size of the slot or aperture in the disk 21 do not exceed the scope of this invention.

It may be desirable to position on the pipe 16 a pressure regulating valve so that the amount of cooling medium dispersed from the member 9 will remain constant, regardless of the degree to which any one port 24 is opened or the number of such ports uncovered by the slot in the disk 21.

The cooling system herein set forth obviates sudden cooling and chilling of the metal, which has heretofore been experienced when other types of cooling systems have been employed.

While it is usually preferable that the mold 125 be cooled substantially concomitantly with 130

the deposition of metal, and while it is preferable that the area of cooling be practically co-extensive with the deposited metal, the cooling may be so arranged as to precede or succeed the deposition, depending upon the extent of cooling demanded. If a section is brought into operation before metal is poured within the area of the mold cooled by that section, a greater cooling would be effected. 5 The reverse of this is equally true. But regardless of the exact time relationship, there will be a gradual and longitudinally progressive cooling of the mold at a determined relationship to the pouring of metal, which will 10 obviate to a great extent, if not altogether, the necessity of an annealing process subsequent to the casting operation.

While I have shown and described the preferred embodiment of my invention, I wish 20 it to be understood that I do not confine myself to the precise details of construction herein set forth, by way of illustration, as it is apparent that many changes and variations may be made therein, by those skilled in the art, 25 without departing from the spirit of the invention, or exceeding the scope of the appended claims.

I claim:

1. A centrifugal casting apparatus comprising a rotary mold, a trough for depositing molten metal in said mold, means for moving said trough axially of said mold, a fluid dispersing member adapted to disperse a cooling medium on said mold, means dividing said member into a plurality of sections, a rotary valve mechanism, a conduit connecting each of said sections with said valve mechanism and means for supplying a cooling medium to said valve mechanism.

40 2. A centrifugal casting apparatus comprising a rotary mold, a trough for depositing molten metal in said mold, means for moving said trough axially of said mold, a fluid dispersing member arranged to disperse a cooling medium on said mold, means dividing said member into a plurality of sections, a rotary valve mechanism, a conduit connecting each of said sections with said valve mechanism and means for supplying a cooling medium to said valve mechanism and means associated with said trough moving means for operating said valve mechanism.

50 3. A centrifugal casting apparatus comprising a rotary mold, a trough for depositing molten metal in said mold, means for moving said trough axially of said mold, a fluid dispersing member positioned to cool said mold, means dividing said member into a plurality of sections, a rotary valve mechanism, means for supplying a cooling medium to said valve mechanism, said valve mechanism comprising a perforated body member, conduits connecting each of said perforations with a section of the dispersing member, an apertured disk positioned to move over said

perforated portion of the valve mechanism and means for rotating said disk to selectively supply a cooling medium to the sections of said member.

4. A centrifugal casting apparatus comprising a rotary mold, a trough for depositing molten metal in said mold, means for moving said trough axially of said mold, a fluid dispersing member positioned to cool said mold, means dividing said member into a plurality of sections, a rotary valve mechanism, means for supplying a cooling medium to said valve mechanism, said valve mechanism comprising a perforated body member, conduits connecting each of said perforations with a section of the dispersing member, an apertured disk positioned to move over said perforated portion of the valve mechanism and means for rotating said disk to selectively supply a cooling medium to the sections of said member, the aperture in the disk being V-shaped so that the flow of cooling medium to any section may be gradually terminated.

5. A centrifugal casting apparatus comprising a rotatable mold, a pouring trough, a cooling system for said mold, comprising a sectional cooling member, conduit means for supplying a cooling medium to said member, and a valve positioned in said conduits, means adapted to be operated for successively admitting a cooling medium to adjacent sections of the cooling member at a predetermined relationship to the deposition of molten metal within the mold.

6. A cooling system for a rotatable mold, comprising a sectional cooling member, individual feed pipes for the sections, a rotary multiple valve communicating with a cooling medium supply and with each of the feed pipes and means for actuating the valve.

7. A centrifugal casting apparatus comprising a rotary mold, a pouring trough associated therewith, a cooling system for said mold including a fluid dispersing member, baffles mounted therein forming sections, an independent feed pipe for each section and a valve for progressively supplying successive adjacent sections with a cooling medium.

8. A centrifugal casting apparatus comprising a rotary mold, a pouring trough, a cooling system for the mold comprising a fluid dispersing member, baffles therein mounted forming fluid tight sections, feed pipes for each section, a valve associated with the feed pipes for controlling the flow of fluid therethrough and adapted to be operated for progressively supplying a cooling medium to adjacent sections in a predetermined relation to the deposition of molten metal within the mold, and means associated with the trough actuating means for operating the valve.

9. A centrifugal casting apparatus comprising a rotary mold, means for pouring molten metal in the mold, a cooling system

for said mold, comprising a sectional cooling member, a rotary multiple valve, a feed pipe for each section communicating with the valve and regulating means for the valve operated by an element actuating the pouring means so that a cooling medium is introduced into the feed pipes progressively at a predetermined rate, and at a certain relationship to the pouring of molten metal within the mold.

10 10. A centrifugal casting apparatus comprising a rotary mold, a pouring trough, a sectional cooling member adjacent said mold and valve means adapted to be actuated independent of said trough for operating independent sections of the cooling member at a predetermined relationship.

11. A centrifugal casting apparatus comprising a rotary mold, a pouring trough, said mold and trough being movable relatively to each other, a cooling member extending the length of the mold, said member having a plurality of cooling sections, valve controlled feed lines for supplying a cooling medium to said sections and means independent of said trough for progressively operating the valves to supply cooling medium to adjacent sections of said member relative to the deposition of metal in said mold.

12. A centrifugal casting apparatus comprising a rotary mold, a pouring trough, a sectional cooling member adjacent said mold, conduits for supplying a cooling medium thereto, a valve for regulating the flow through the conduits, means independent of but synchronized with movement of said trough for progressively operating the valve for cooling successive adjacent sections of said member, and actuating means for said operating means.

13. A centrifugal casting apparatus comprising a rotary mold, a pouring trough associated therewith, a fluid dispersing member positioned above said mold, a plurality of partitions in said member dividing the latter into a plurality of dispersing sections, a cooling medium supplying conduit, a valve having a plurality of individual compartments in communication with the dispersing sections and means for selectively establishing communication between said conduits and said compartments.

In testimony whereof I affix my signature.
FRANK G. CARRINGTON.
